UNITED STATES PATENT OFFICE.

ROY D. FRITZ, OF AKRON, OHIO, ASSIGNOR TO THE B. F. GOODRICH COMPANY, OF NEW YORK, N. Y., A CORPORATION OF NEW YORK.

VULCANIZING APPARATUS.

Application filed July 2, 1926. Serial No. 120,131.

This invention relates to apparatus for vulcanizing rubber articles such as inner tubes for vehicle tires, for example, and is especially applicable to procedure in which the articles are submerged in water or other liquid prior to or during the vulcanizing period.

My chief objects are to provide improved apparatus wherein a vulcanizing fluid conveniently and economically may be maintained under super-atmospheric pressure between vulcanizing periods, as in so maintaining a body of water to conserve the heat therein for vulcanization or treatment of a succeeding batch of articles; to provide for safety, economy of heat and facility of operation; to provide for accurate control of the temperature of the vulcanizing fluid; to provide for economy in equipment cost; to conserve floor space; to provide for simplicity of apparatus; and to provide for effective circulation of the heating medium about the articles to be vulcanized.

More detailed objects will be manifest.

Of the accompanying drawings:

Fig. 1 is a vertical section of a vulcanizer embodying and adapted to carry out my invention in its preferred form, parts of the apparatus being broken away to foreshorten the figure.

Fig. 2 is a vertical section of a modification.

Referring to the drawings, the preferred apparatus shown in Fig. 1 comprises a vertical, cylindrical vulcanizing-tank 10 into which a ram 11 projects from below, the ram having at its upper end an imperforate head 12 adapted to seal, about its outer margin, against the lower face of an annular shoulder or flange 13 secured and sealed to and projecting inward from the inner face of the tank 10 at about the middle thereof from top to bottom. Mounted in a recess in the upper face of the ram-head 12 is a gasket 14, here shown as a lip-gasket, for sealing the ram-head against the flange 13. The ram-head is thus adapted, when the ram is elevated, to divide the tank 10 into an upper chamber 15 and a lower chamber 16, the tank 10 being provided at its top with a cover 17 of the breech-block type commonly used upon vulcanizers.

A pipe 18 leads through the wall of the tank 10 into the upper part of the chamber 15, and a pipe 18^a leads through the wall

at a low part thereof and terminates at the lowermost part of the chamber 15, for conducting steam or other fluid into the said chamber or for venting a fluid therefrom, and pipes 19, 19^a communicate, through the base of the tank, with the lower part of the lower chamber 16 for conducting a fluid into or out of the lower chamber. A pipe 20 provided with a shut-off valve 21 communicates at its upper end with the upper chamber 15 and at its lower end with the lower chamber 16, constituting a by-pass around the partition formed by the ram-head 12 and flange 13, the pipe 20 thus being adapted for equalizing the pressure in the chambers 15 and 16 while the ram-head 12 remains in its uppermost position in sealed relation to the flange 13.

The tank 10 is surrounded by a steam-jacket 22, here shown as being limited to the region of the lower chamber 16, the said steam-jacket being provided with inlet and outlet pipes 23, 24 for circulating a heating fluid therethrough.

The upper face of the ram-head 12 is formed with dowel recesses such as the recess 25 to receive respective dowel pins, such as the pin 26, projecting downward from the base 27 of a sling 28 which is provided with a bale 29 having an eye 30 adapted to be engaged by the hook of an overhead hoist for lowering the sling onto and lifting it from the ram-head 12, in mounting the sling in and removing it from the vulcanizer.

The dowel pins 26 are formed with shoulders adapted to seat against the upper face of the ram-head 12 so as to hold the base 27 of the sling spaced above the ram-head, for the free circulation of fluid, and the said base 27 is formed as a grating, so that the fluid may pass therethrough. Projecting upward from the bars of the grating are pins 31, 31 adapted to enter and to position the lower ends of inner tube mandrels 32, 32 placed thereover while permitting fluid to circulate into or out of the mandrels in circulating therethrough for the effective heating of inner tube 33, 33, mounted upon the mandrels.

For accurately holding the mandrels in upright positions in the sling 28 the latter is provided near its top with a horizontal plate 34 which is formed with apertures 36, 36 to receive and hold in place the upper ends of the respective mandrels 32, the sling

thus being adapted for the mounting of the tube mandrels therein in substantially the manner in which billiard cues are mounted in their rack. The apertures 36 are preferably somewhat larger than the mandrels, for the easy insertion of the latter and to permit circulation of water, outside of the mandrels, through the plate.

In the preferred operation of the apparatus, the vulcanizer being empty and the cover 17 removed, the ram 11 is raised to seal its head 12 against the flange 13 and thus close the lower chamber 16. A body of water 37, which may have been pre-heated, is then run into the lower chamber 16 through the pipe 19 until the lower chamber is almost filled with water, air being vented from the chamber 16 through the pipe 20 as may be necessary or desired, although in the preferred practice of vulcanizing the tubes while they are submerged in water at a pressure greater than its temperature pressure the desired pressure may be built up in the chamber 16 by leaving the valve 21 closed during the influx, or during the latter part of the influx, of the water. Steam is circulated through the steam-jacket 22 in order to raise the water to or maintain it at vulcanizing temperature, and a suitable thermostatic control (not shown) may be provided for controlling the water temperature.

The sling 28 carrying the mandrels 32 and inner tubes 33 thereon is then lowered into the vulcanizer and seated upon the ram-head 12, after which the cover 17 is mounted upon the vulcanizer, and such preliminary treatment as may be desired is given to the tubes 33. For example, steam may be slowly admitted from the lower chamber 16 through the pipe 20 into the upper chamber 15 while air is vented from the latter through the pipe 18 or 18^a, the circulation of steam through the upper chamber 15 at low pressure serving moderately to heat and to soften the inner tubes 33.

The outlet represented by the pipe 18 or 18^a is then closed while the valve 21 of the by-pass 20 is left open until the pressures in the lower chamber 16 and the upper chamber 15 have been equalized by the passage of steam through the by-pass. When the pressures in the two chambers 15, 16 have thus been equalized, the ram 11 with the sling 28 thereon is lowered until the tubes 33 and mandrels 32 are completely submerged in the water 37 and, if a pressure in the water greater than its temperature pressure is desired, such pressure is obtained by conducting high pressure air into the chambers 15 and 16 through the pipe 18, or by conducting additional high pressure water into the vulcanizer through the pipe 19.

The tubes are permitted to remain in the high pressure water at vulcanizing tempera-

ture until vulcanization is complete, and the valve 21 is closed either during or at the end of the vulcanizing period.

The vulcanization being completed, the ram 11 is raised to lift the sling into the upper chamber 15 and to seal the ram-head 12 against the flange 13. The pressure in the upper chamber 15 is then reduced to atmospheric pressure by venting the said chamber through the pipe 18, the cover 17 is taken off, and the sling 28 with the vulcanized tubes thereon is lifted from the vulcanizer, while the water 37 in the lower chamber 16 continues to be held at or near the vulcanizing temperature and at a pressure equal to or greater than its pressure temperature, to conserve the heat of the water for a succeeding vulcanizing operation.

The operation as described may be varied by subjecting the vulcanized tubes to a cooling operation while maintaining them under high fluid pressure in the upper chamber 15, as by maintaining a high fluid pressure in the said chamber by conducting compressed air thereinto through the pipe 18^a while conducting a cooling fluid such as water into the chamber 15 through the pipe 18, and permissibly discharging it onto the tubes, the cooling water then being drained off from the chamber 15 through the pipe 18^a, so that it will not subsequently be mixed with the high temperature water 37 in the lower chamber 16.

The operation may also be varied by maintaining the water 37 at an elevated temperature less than the vulcanizing temperature, lowering the tubes thereinto to soften them, building up a fluid pressure in the vulcanizer to cause the water to press and compact the tubes against the mandrels, and thereafter raising the tubes into the upper chamber 15 and curing them in steam by circulating steam in the said upper chamber by means of the pipes 18 and 18^a.

The apparatus is of very simple construction and yet permits wide variation of the treatment given to the articles to be vulcanized, and the vertical position of the inner tube mandrels permits an effective circulation of the heating medium through the mandrels, especially when the heating means, such as the steam-jacket 22, is so positioned as to cause an effective gravity circulation of the water 37.

The water 37 may be held at a very high pressure with a high degree of safety between vulcanizing operations, since the large area of the ram-head 12 results in such high pressure upon the gasket 14 as to provide a perfect seal, whether the said gasket be of the lip type or of the simple compression type, and the ram-head is positively limited in its upper movement by the strong and securely mounted flange 13.

Extensive or elaborate systems of piping are avoided while very desirable variations of the vulcanizing fluid and of temperature and pressure schedules are made possible, and the several other advantages expressed or implied in the above statement of objects may be obtained.

In the modification shown in Fig. 2 a horizontal vulcanizing tank 40 is shown, extending into which from below are a pair of rams 41, 41 having secured to their upper ends an air-lock tube 42 having its rear end permanently closed and having at its front end a locking collar 43 of the breech-block type adapted to mate with locking means formed on the adjacent end of a tube 44 which is slidably sealed in a gland 45 mounted in the adjacent end wall of the tank, the tube 44 being provided at its outer end with a door 45^a and adapted to be slid inward and to be held back in its outward movement by means of a screw device 44^a, and, when in its innermost position, to be locked to the tube 42 in sealed relation thereto. The screw device 44^a is hinged to the vulcanizer at 44^b, 44^b, so as to be swung aside for removal or insertion of the articles, and the screw of the said device is adapted to bear upon a stud 44^c projecting rigidly from the door 45^a for a sufficient distance to give stability to the screw device in operative position.

The outer end of the tube 44, outside of the tank, is provided with a door 45 traversed by a vent pipe 46 having a stop-valve 47 for reducing pressure within the tubes 42 and 44 when the said tubes are locked together in sealed relation.

The tank 40 is provided with an air or steam pipe 48 at its top and a drain or vent pipe 49 at its bottom, for suitably supplying fluid thereto or venting it therefrom, and a steam-jacket 50 having inlet pipes 51, 52 may be provided.

In the operation of this modified type of apparatus, the parts being in the positions shown in Fig. 2, the tube 44 is slid inward and engaged with the tube 42 so that the interiors of the tubes are out of communication with the interior of the tank 40. The tubes 42, 44 are then vented through the pipe 46 to reduce the pressure within them to atmospheric pressure, and the door 45 is then opened and a quantity of articles to be vulcanized are passed through the tube 44, from the exterior of the vulcanizer, into the tube 42. The door 45 and the vent pipe 46 are then closed, the tube 44 is turned to disconnect it from the tube 42, the pressure within the tank 40 then forcing the tube 44 to its

outermost position, where, in conjunction with its door 45, it serves as a closure member for the tank 40, and the tube 42 with the articles to be vulcanized therein is lowered by means of the rams 41 into a body of water contained in the tank 40, the water entering the tube 42 and surrounding the articles.

When articles have remained in the water for a sufficient time to be vulcanized the tube 42 is raised from the water, the tube 44 is forced inward and connected with the tube 42, and the two tubes are vented through the pipe 46, after which the door 45 is opened and the articles are removed. A new batch of articles is then passed into the tube 42 and the operation as described is repeated.

I claim:

1. A vulcanizer comprising a tank, a ram having its head within the tank for lowering and raising articles therein, and means on the side wall of the tank at an intermediate part thereof for sealing against the ram head to divide the tank into two compartments.

2. A vulcanizer comprising a tank, a liquid bath partly filling the tank, means for maintaining the said liquid bath at vulcanizing temperature, vertically reciprocable means for lowering and raising articles in the tank to submerge them in and lift them from the liquid bath while the tank is closed, and a gas lock for passing articles into the tank.

3. A vulcanizer comprising a tank, means for lowering and raising articles in the tank while the tank is closed, and means adapted to seal against the said lowering and raising means and therewith to constitute a gas lock for passing articles into the tank.

4. A vulcanizer comprising a tank, sealing means for dividing the tank into an upper and a lower compartment at will, and means for transferring articles from one of the compartments to the other while the tank is closed.

5. A vulcanizer comprising a tank, a ram having its head within the tank for lowering and raising articles therein, means on the side wall of the tank at an intermediate part thereof for sealing against the ram head to divide the tank into an upper and a lower compartment, and a valve for equalizing pressures in the two compartments.

In witness whereof I have hereunto set my hand this 29th day of June, 1926.

ROY D. FRITZ.
